UNITED STATES PATENT OFFICE.

HUBERT W. MORGAN AND JAMES A. LAKIN, OF WESTFIELD, MASS.

CASKET-HANDLE.

SPECIFICATION forming part of Letters Patent No. 245,203, dated August 2, 1881.

Application filed June 6, 1881. (No model.)

To all whom it may concern:

Be it known that we, HUBERT W. MORGAN and JAMES A. LAKIN, of Westfield, in the county of Hampden and State of Massachusetts, have invented a new and useful Improvement in Casket-handles, of which the following is a specification and description.

The object of our invention is to provide a casket - handle having its arm and also its eye divided, so as to open or enlarge the eye to receive the handle, and when the two parts of the arm are secured together one of its parts locks the arm into the socket which is secured to the casket, and causes the arm to move in the socket with the desired amount of friction; and we accomplish this by the means substantially as hereinafter described, and illustrated in the accompanying drawings, in which—

Figure I is a front view of a socket adapted to be secured to the casket, and the arm secured therein, and made according to our invention. Fig. II is a top view of the same. Fig. III is a side view of the arm, and the socket in it which it is secured. Fig. IV is a rear view of the socket and the arm secured therein. Fig. V is a vertical longitudinal section of the arm and the socket at line B; and Fig. VI is a side view of the arm, showing the two portions of the arm moved apart and the eye opened or enlarged to receive the handle.

In the drawings, 2 denotes the socket, which is flanged and adapted to be secured to the casket by screws, and which socket is open from one side to the other, and is provided on the inside with two inwardly-cylindrical trunnions, as 6.

The arm 4 is provided at one end with a partially-spherical-shaped head, as 5, made to approximately fit the correspondingly-shaped upper portion of the opening in the socket, and also with a shoulder, as 3, at the lower part of the head, to approximately fit, and bear against the end of the socket. This head is also provided with a recess on each side, as 7, which recesses are open at the back side to receive the trunnions 6 in the socket, and which are provided with a curved shoulder at the front side to approximately fit and bear against the trunnions.

The arm 4 is divided or made in two parts,

as shown clearly in Figs. III and VI, one portion 4 being connected at the lower end with the eye 12, and the latter being connected with the other divided portion 10 of the arm, the eye being separated on the line of division of the arm, as shown clearly in Figs. III and VI, and the extreme end of the divided portion 10 of the arm is extended out on each side, so as to bear against the trunnions on the back side, as shown clearly in Fig. IV, and in dotted lines in the other figures.

A screw, 11, inserted in the part 10 of the arm, and turned into the main part of the arm, secures the two parts of the arm together and in place, and also secures the eye firmly on the handle 13, and also holds the extreme end, 8, which I denominate the "friction-plate" for convenience in this description, against the trunnions 6 on the back side with more or less friction, according as the screw 11 is turned in more or less to cause the arm 4 to move with the desired degree of friction in the socket and cause the arm to remain in any position of elevation into which it may be placed, if required, as shown in dotted lines in Fig. III.

The eye 12, which receives the handle 13, may be made with a shoulder, 9, at each side, to reduce the diameter of the inner portion of the eye, with a corresponding reduction in diameter of the handle, with a shoulder at each side, as shown clearly in Figs. I, III, and V, for the purpose of assisting in holding the handle in its desired relative position with the arm.

Heretofore in the manufacture of casket-handles it has been necessary to construct the handles in different and separate parts, and to cover or trim each part separately with its textile covering, because it is desirable, to give the best and proper proportions, that the ends 14 should be considerably larger in diameter than the part 13 between them; and as the eye 12 has hitherto been made solid, the ends 14 usually being doweled into the part 13, the handle has been taken apart by removing one of the ends 14 and the middle portion, 13, inserted into the eye and the end replaced again. It is much more expensive to construct the handle in separate pieces, and by our invention we avoid this expense, besides all the trouble

incident to securing the handle into the eye, as it is usually fastened by turning a screw through the eye into the handle.

By making the arm divided and securing the part 10 to the main portion of the arm by the binding-screw 11 we are enabled to make the handle 13 solid, whether of wood or metal, and to place it in the eye 12 by bending the part 10 away from the main portion of the arm 4, as shown clearly in Fig. VI, and opening the eye 12 far enough to insert the handle 13, the arm and eye being made of some suitable metal that will bend sufficiently for this purpose. After the handle is inserted in the eye the head 15 is inserted in the socket by holding the arm 4 nearly parallel with the flange of the socket and inserting the trunnions into the recesses 7, and then bending the part 10 up against the part 4 and turning in the screw 11, securing 20 the handle 13 in the eye 12, and also pressing the friction-plate 8 in against the trunnions 6, so as to cause the arm 4 to move in the socket with the desired degree of friction, all with one fastening-screw.

25 The handles 13, with the parts 14, being all made in one piece and bored out at each end to receive the metal tips 15, may be either plaited with twine or thread of any desired fabric, or with cloth of any suitable kind, for its 30 whole length, and the metal tips be afterward inserted into the ends of the handle, and, if desired, plated metal rings may afterward be sprung onto the covered handle to improve the appearance and produce the desired contrast. 35 It is, of course, evident that the arm 4 may be secured in the socket by any other desirable and convenient means, and yet the arm be divided longitudinally, so as to open the eye 12 to receive a solid handle or one made in one 40 piece.

It is obvious that one socket and arm may

be used to secure the handle to the casket with the eye about midway the length of the handle, as shown in Figs. I and II, or two arms and sockets may be used to each handle, with 45 one eye near each end of the handle.

Having thus described our invention, what we claim as new is—

1. In an improved casket-handle, the combination, with a socket adapted to be secured to the casket, of a divided arm, having an eye made thereon which is adapted to be opened to receive the handle by bending the two parts of said arm away from each other, and in which eye the handle is secured by forcing the two parts 55 of the arm together and there securing them by a screw, substantially as described.

2. In an improved casket-handle, the combination of a socket adapted to be secured to the casket and provided with two inwardly-projecting trunnions, a divided arm provided with a recess, as 7, in each side of its head to receive the said trunnions, and with one part of said arm extending to a point behind and adapted to be pressed against said trunnions 60 by a screw turned into said arm, whereby the handle is secured to said arm and the latter moved in its socket with the desired amount of friction, substantially as described.

3. In an improved casket-handle, the combination of a socket adapted to be secured to a casket, a divided arm secured in said socket, and a handle made in one piece, covered with a textile fabric and recessed to receive a shoulder in the eye made on said arm, and secured 70 in said eye by a screw securing the two parts of said arm together, substantially as described.

HUBERT W. MORGAN.

JAMES A. LAKIN.
